UNITED STATES PATENT OFFICE.

GUY DINCOGNITO, OF CHICAGO, ILLINOIS.

WIRE JOINT.

Application filed January 6, 1923. Serial No. 610,931.

To all whom it may concern:

Be it known that I, GUY DINCOGNITO, a citizen of the United States, and a resident of the city of Chicago, county of Cook, and 5 State of Illinois, have invented certain new and useful Improvements in Wire Joints, of which the following is a specification.

This invention relates to wire joints, and has for its object the provision of joints of 10 this character which will be extremely neat in appearance, easily formed, and strong and durable in construction.

Other objects will appear hereinafter.

The invention consists in the combinations 15 and arrangements of parts hereinafter described and claimed.

The invention will be best understood by reference to the accompanying drawings forming a part of this specification and in 20 which—

Fig. 1 is a front elevation of a doubling joint showing the members disposed side by side and having their abutting edges bevelled so as to reduce the width of the double 25 joint;

Fig. 2 is a view partially in section on line 2—2 of Fig. 1;

Fig. 3 is a front elevation of a double joint showing the members provided with 30 two fingers or portions each, and the fingers or the portions of the opposite members having their abutting edges bevelled so as to reduce the width of the joint; and

Fig. 4 is a view partially in section on 35 line 4—4 of Fig. 3.

It is common practice in forming joints between the ends of web wires, and the frame or supporting wires, of articles such as baskets, wire lamp shade frames, dish 40 draining receptacles, soap dishes and other articles made of wire, to secure the ends of the web wires to the frame or supporting wires by bending said ends about the supporting wire, and then applying solder.

45 This provides a joint which is strong and durable but is open to the objection that the bent end of the web wire projects from the surface of the supporting wire a distance equal to the thickness of the web wire 50 throughout its bent portion, so that by employing a joint of this character the symmetry of the article is affected, as well as a projection formed which is likely to catch into articles of clothing or the like, or injure the hands of a person using an article

containing such joints. My invention is designed to eliminate, as far as possible, this unsightly and inconvenient joint, and provide a joint which projects but a small distance from the supporting wire, and is 60 smooth and attractive appearance.

The joints are particularly adapted to be utilized in connection with so called cross or double joints, as shown in the drawings. Referring to Figs. 1 and 2, 18 represents a 65 supporting wire, and 19 and 20 represent oppositely disposed web wires connected to the supporting wire 18 by reduced joints. In addition the edges of such joints are oppositely bevelled in a suitable manner as 70 shown at 21, so as to reduce the width of the joint. By this arrangement it is apparent that not only the depth and height of the joints are reduced, but the width thereof is 75 also greatly reduced, thus producing an extremely strong and inconspicuous joint, in which the wires 19 and 20 are disposed as closely end to end as possible so as to form a substantially continuous wire despite the jointure of the same to the supporting wire. 80

In Figs. 3 and 4, inclusive, modified joints are shown. In such figures, 22 represents a supporting wire, to which the ends of the oppositely disposed members 23 and 24 are connected. The adjacent ends of the members 23 and 24 are of the split type which ends when used in a double joint of the character shown in Fig. 3, have their side 85 abutting edges bevelled as shown at 25, so as to reduce the width of the joint. By this arrangement not only will a joint be provided in which the joined wires are substantially disposed end to end, but such wires are disposed in the same lateral plane. 90 With this construction a thin joint is produced and only a small measure of strength is sacrificed by beveling and tapering the ends of the supported wires, which may be compensated for by using slightly heavier 95 wire. 100

While I have illustrated and described the preferred form of construction for carrying my invention into effect, this is capable of variation and modification without departing from the spirit of the invention. I, 105 therefore, do not wish to be limited to the precise details of construction set forth, but desire to avail myself of such variations and modifications as come within the scope of the appended claims. 110

Having described my invention, what I claim as new and desire to secure by Letters Patent is:

A joint of the character described comprising a supporting member, a second member having its end reduced and tapering to its extremity and clasped about said supporting member, said reduced portion having its side edge bevelled, and another mem-

ber having its end reduced and tapering to 10 its extremity and clasped about said supporting member, said last member having its side edge oppositely bevelled and abutting against a bevelled edge of said second member. 15

In testimony whereof I have signed my name to this specification.

GUY DINCOGNITO.
